UNITED STATES PATENT OFFICE.

WINFIELD H. DAVIS, OF RUTHERFORD, NEW JERSEY.

ADJUSTABLE TRACK-GAGE.

1,153,769.

Specification of Letters Patent. Patented Sept. 14, 1915.

Application filed June 29, 1914. Serial No. 847,888.

To all whom it may concern:

Be it known that I, WINFIELD H. DAVIS, a citizen of the United States, and a resident of Rutherford, in the county of Bergen and State of New Jersey, have invented a new and Improved Adjustable Track-Gage, of which the following is a full, clear, and exact description.

This invention relates to improvements in gages, and has for an object to provide an improved construction which may be used upon a track at any point.

Another object of the invention is to provide an improved track gage which is formed with an adjustable part for allowing the gage to be shortened or lengthened as occasion may demand, this construction being such as to present an adjustable feature without weakening the general structure of the gage.

A further object of the invention is to provide an adjustable construction for a track gage which cannot be readily broken, and which may be easily and quickly adjusted for allowing the sliding members forming part thereof to be so placed as to produce a lengthening or shortening of the gage.

In carrying out the objects of the invention a cross bar of any usual construction is provided with a track engaging end which may also be of any desired construction. Opposite to the track engaging end is a specially constructed end formed throughout with the various parts so braced that the same will not readily break even under rough usage. This specially constructed end is provided with a plurality of sliding plates when when in one position will lengthen the gage and when in another will shorten the same. A suitable retaining bolt is provided for always holding these plates correctly in position whether adjusted to occupy one position or another.

In the accompanying drawings, Figure 1 is a longitudinal horizontal section through one end of a track gage, the same disclosing an embodiment of the invention; Fig. 2 is a longitudinal vertical section through the structure shown in Fig. 1; Fig. 3 is a sectional view through Fig. 2 approximately on line 3—3; Fig. 4 is a view similar to Fig. 3 but with the adjusting plates in an elevated position; Fig. 5 is a side view of an entire gage, the same embodying the invention.

Referring to the accompanying drawings by numerals, 1 indicates a cross bar which may be of any shape and size but preferably is tubular as shown in Figs. 1 and 2. The 60 cross bar 1 is provided with an end member or head 2 which is formed with a measuring face 3 and a supporting face 4, face 4 resting on top of the rail while face 3 engages the edge of the ball of the rail. Arranged 65 on the opposite end of bar 1 to head 2 is a specially constructed head 5, which head is formed so as to resist more or less rough usage while allowing an adjustment at any time so as to adapt the gage to all conditions 70 presented in the construction of a railroad. The head 5 is provided with a sleeve 6 (Figs. 1 and 2) designed to fit over the end of bar 1. However, in order to prevent the short circuiting of the block signals of the 75 track an insulating sleeve 7 is provided through which a clamping and retaining rivet 9 passes. All of these parts are adapted to fit perfectly tight so that there will be no movement of the head independent of 80 bar 1. The head 5 is preferably a casting of some good material, and is provided with what may be termed a transverse wall 10 merging into tube or sleeve 6, and also into a plurality of fins or braces 11 whereby the 85 wall 10 is reinforced throughout. Parallel with the transverse wall 10 is a second transverse wall 12 which extends downwardly to a supporting face 13 as shown in Fig. 2.

A suitable space or chamber 14 is provided between walls 10 and 12, which chamber is bound on each side by the walls 15 and 16. It is to be noted that the walls 15 and 16 are of the same length as the wall 12 and merge into walls 10 and 12, whereby 90 a strong stiff structure is presented in which chamber 10 is formed, said chamber being designed to receive a plurality of plates as hereinafter fully described. The lower part of wall 12 merges into a sleeve 17 which carries a smooth bore 18 and an enlarged bore 19. The sleeve 17 is braced by suitable braces 20 for strengthening and stiffening the same. The sleeve 17 is hollowed out at 100 21 whereby the end of pin 22 is protected, and also the threaded sleeve 23 is protected. The end of the pin 22 adjacent sleeve 23 is provided with a groove 24 so as to be easily grasped by the fingers of the operator and moved against the action of spring 25, which spring is arranged in bore 18 and presses against sleeve 23 and against an enlarge- 105 110

ment 26 on pin 22. The enlargement 26 may be formed integral with pin 22 or may be secured thereto in any desired way. It is to be noted that the spring 25 normally holds 5 the pin 22 in the position shown in Figs. 1 and 2.

Arranged in the chamber 14 are a plurality of specially constructed plates 27, which plates are preferably of the same 10 thickness. The various plates 27 are uniform in shape as shown in Figs. 3 and 4 and loosely fit in the chamber 14. The plates when elevated are supported by pin 22 as shown in Figs. 2 and 4, but when lowered 15 as shown in Fig. 3 the plates are supported by pins 28 and 29, which pins engage shoulders 30 and 31. Each of the plates is formed with a cut-out portion 32, and also a cut-out portion 33, whereby shoulders 30 and 31 are formed, and also shoulders 34 20 and 35 are formed, said shoulders 34 and 35 limiting the movement of the plates when the gage is turned over and the pin 22 is moved out of engagement with the plates. 25 When the pin 22 is moved against spring 25 out of engagement with all of the plates and the gage turned over the various plates will drop by gravity to substantially the position shown in Fig. 4, and will rest on the pins 30 28 and 29. The pins 28 and 29 may be inserted in any desired way, as for instance, by inserting the same through the sleeve. This would, of course, necessitate using pins 35 having heads only at one end and then upsetting or riveting the opposite end by any desired form of tool. When the gage is reversed or moved rightside up the weight of the plates will be supported by pin 22, the same being allowed to pass through the apertures 36 of the various plates 27. It will 40 be noted that the various plates are also provided with apertures 37 which accommodate the pin 22 when the plates are in a lowered position as shown in Fig. 3. From 45 Fig. 2 it will be observed that the wall 10 is cut away for forming a chamber 38 into which the rounded end of pin 22 extends while the enlargement 26 is pressing against the plates. The action of the enlargement 50 or stop 26 is such as to cause all of the plates to be pressed tightly together. It will also be noted that the chamber 14 is formed slightly larger than all of the plates so as to allow a free action of the plates. When 55 one or more of the plates are lowered, as shown in Figs. 2 and 3, the same are stacked on what may be termed the measuring face 5', which measuring face is designed to be spaced from the measuring face 3 the exact 60 distance between the insides of balls of rails on a straight track. When it is desired to use the gage on a curve, one or more of the plates 27 are moved to the position shown in Figs. 2 and 3. If the curve is a comparatively long curve only one plate is used. If 65

a shorter curve two plates are used and so on for the full limit of plates as extra width is necessary for shorter curves. This is to prevent a binding action between the drivers of the engine and the rails, which binding action would either spread the rails or derail the engine. By using the plates as described the measuring face 5' is lengthened or moved away from the measuring face 3, and such measurement is exact as the 70 plates 27 are designed to be of a certain thickness. The engineer in directing the placing of a curve can mention that one or more plates are to be used on the curve so that the men doing the work will know exactly how wide the track is to be at the curve. 75

What I claim is—

1. In a gage of the character described, a head provided with an extension, having a 85 contact surface and means defining a chamber, a centrally arranged movable pin arranged to project across said chamber, and a plurality of sliding plates arranged in said chamber and guided in their movement 90 by the walls of said chamber, each of said sliding plates being provided with a pair of apertures for accommodating at different times said pin, whereby any of said plates may be held in an elevated or in a lowered 95 position at will for lengthening and shortening the head as desired.

2. In a track gage of the character described, an integrally constructed head therefor, said head comprising walls defining a 100 chamber and a plurality of stiffening and bracing ribs for said walls, a reciprocating pin arranged to move centrally and axially of the gage, a plurality of slidable plates arranged in said chamber, each of said plates being provided with a pair of apertures for 105 accommodating part of said pin, whereby any of the plates may be locked in an elevated or a lowered position and a pair of pins for limiting the sliding movement of said plates. 110

3. In a track gage of the character described, a head therefor, said head comprising a casing formed with a measuring face, a plurality of identically constructed slideable plates arranged in said casing and adapted to be moved to a position in front of said face and from a position in front of said face, each of said plates being formed with a pair of spaced apertures and also with a notched-out portion on each edge, a spring-pressed pin carried by said casing adapted to be inserted into either of said apertures for locking said plates in an operative or an inoperative position, and means carried by said casing engaging the plates at the respective ends of said notched-out portions for supporting the plates independent of said pin when in an operative position. 115 120 125

4. In a track gage of the character described, a head connected with the body of 130

the gage, said head being formed from a single casting and provided with a chamber merging into a measuring face, and a horizontal supporting face, a plurality of slideable plates arranged in said chamber and adapted to slide to a position in front of said measuring face, and means for holding said plates either in said chamber or against said measuring face.

10 5. In a track gage of the character described, a head connected to the body of the gage and formed with a measuring face and with a supporting face, a plurality of slideable plates arranged in said head and adapted to slide to a position in front of said measuring face and from said position, a sliding pin for locking said plates in either of their positions, stationary supporting pins arranged on each side of said first mentioned pin, each of said sliding plates being formed with an elongated notch on each edge, whereby upper and lower shoulders are provided on each edge of each plate, said shoulders being designed to rest against said supporting pins according to the position of the plates, each of said plates being provided with an aperture substantially in line with each pair of shoulders, said last mentioned apertures being adapted to accommodate said first mentioned pin so as to lock the plates opposite said measuring face or away from said measuring face at will.

6. In a track gage of the character described, a head connected with the body of the gage, said head being formed with a casting having reinforcing webs for resisting rough usage, a plurality of slideable plates

arranged in said head, each of said plates being formed with a pair of apertures and with pairs of shoulders, a reciprocating pin 40 designed to project through one of the apertures in the respective plates for locking the plates in an elevated position and through the other aperture for locking the plates in a lowered position, and a pair of supporting 45 pins arranged to engage said shoulders at different times, one set of shoulders engaging the pins when the gage is inverted and the other set of shoulders engaging said pins when the gage is in correct position and the 50 plates move to an operative position.

7. A track gage comprising a body and a head at each end, one of said heads being provided with a depending face and a horizontally extending section having a contact 55 surface, said depending face being braced by a web and said extension being provided with a bracing member, said head adjacent said extension being provided with a chamber and said head being formed of one integral piece, and a plurality of plates or aliners normally arranged in said chamber, said plates or aliners being capable of sufficient movement to allow part of the respective plates to be moved to a position in front 60 of said depending face.

In testimony whereof I have signed my name to this specification in the presence of two subscribing witnesses.
